Primary Examiner — Mimosa De

(74) Attorney, Agent, or Firm — Garcia-Zamor
Intellectual Property Law, LLC; Ruy Garcia-Zamor(57) **CLAIM**

We claim a new ornamental design for a boat chair, as shown and described.

DESCRIPTION

FIG. 1 is a top front perspective view of a boat chair according to the present invention;
FIG. 2 is a front side elevational view of the boat chair of FIG. 1;
FIG. 3 is a rear side elevational view of the boat chair of FIG. 1;
FIG. 4 is a left side elevational view of the boat chair of FIG. 1;
FIG. 5 is a right side elevational of the boat chair of FIG. 1;
FIG. 6 is a top plan view of the boat chair of FIG. 1;
FIG. 7 is a bottom plan view of the boat chair of FIG. 1;
FIG. 8 is a rear left bottom perspective view of the boat chair of FIG. 1;
FIG. 9 is rear right top perspective view of the boat chair of FIG. 1; and,
FIG. 10 is a front right bottom perspective view of the boat chair of FIG. 1.
The broken lines in FIGS. 1-10 represent environment and are for illustrative purposes only and do not constitute part of the claimed design.

1 Claim, 10 Drawing Sheets(56)
